CLAIM

The ornamental design for a top portion for a bib clip, as shown and described.

DESCRIPTION

FIG. 1 is a top, front, right perspective of a top portion for a bib clip showing our new design;

FIG. 2 is a bottom, front, left perspective view thereof;

FIG. 3 is a front elevation view thereof;

FIG. 4 is a rear elevation view thereof; and,

FIG. 5 is a left side elevation view thereof.

The broken lines showing in FIGS. 1–5 are for illustrative purposes only and form no part of the claimed design.
